G. HUNT

INTERNAL COMBUSTION ENGINE

Filed Oct. 8, 1924

INVENTOR
GEORGE HUNT
BY
P. T. Powers
ATTORNEY

UNITED STATES PATENT OFFICE.

GEORGE HUNT, OF DETROIT, MICHIGAN, ASSIGNOR TO THE STUDEBAKER CORPORATION, OF SOUTH BEND, INDIANA, A CORPORATION OF NEW JERSEY.

INTERNAL-COMBUSTION ENGINE.

Application filed October 8, 1924. Serial No. 742,474.

To all whom it may concern:

Be it known that I, GEORGE HUNT, a citizen of the United States of America, and resident of Detroit, in the county of Wayne 5 and State of Michigan, have invented certain new and useful Improvements in Internal-Combustion Engines, of which the following is a specification.

This invention relates to engine lubrication and particularly to that type commonly known as the "splash" system in which oil dips carried by the connecting rods dip into oil receiving troughs during rotation of the crank shaft and splash the oil on to various operating parts and, in some cases, force oil through the dip to the crank pins.

An object of this invention is to provide a removable oil dip for a connecting rod.

Another object is to provide a removable oil dip for a connecting rod which is secured in place by the same bolts that hold the bearing cap in place.

Another object is to provide a connecting rod oil dip that is manufactured mainly of sheet metal independently of the connecting rod and is removably secured thereto.

A further object is to provide a connecting rod oil dip composed of a sheet metal securing part provided with openings to receive the connecting rod bolts to secure it in place, and a central opening in which a tubular dip member is secured, the dip member projecting up through the securing part and into an opening in the connecting rod cap leading to the bearing surface thereof.

The above being among the objects of the present invention, the same consists of certain features of construction and combinations of parts to be hereinafter described with reference to the accompanying drawing, and then claimed, having the above and other objects in view.

In the accompanying drawing which illustrates a suitable embodiment of the present invention, and in which like numerals refer to like parts throughout the several views,

Figure 1 is a sectional view taken transversely through an internal combustion engine in which the present invention is embodied.

Figure 2 is an enlarged partially broken view of the lower end of the connecting rod of the engine shown in Figure 1, the different parts being shown separated and in

the position in which they are progressively assembled.

Figure 3 is a longitudinal section taken vertically through the assembled oil dip member.

Figure 4 is a transverse section of the assembled oil dip member taken on the line 4-4 of Figure 3.

Figure 5 is a perspective view of the tubular dip portion only of the oil dip member.

The internal combustion engine shown in Figure 1 is of the conventional type having an oil pan 10, crank case 11, cylinder block 12 and cylinder head 13. A cylinder liner 14 is received in the cylinder block 12 and projects down into the crank case 11, it being held in such position by a centrally located outward peripheral flange which is clamped between the cylinder block 12 and crank case 11. A piston 15 adapted to reciprocate in the liner 14 is connected to the crank pin 16 of the crank shaft 17 by means of the connecting rod 18. Suitably operated valves 19 are provided for controlling the entrance of combustible gas to and discharge of exhaust gas from the combustion chamber 20 through passages such as 21. The lower or big end of the connecting rod 18 is provided with a suitable cap 22 which extends around half of the crank pin 16 and is secured to the connecting rod 18 by the bolts 23 and nuts 24. That portion of the connecting rod 18 and cap 22 which receives the crank pin 16 is lined with a suitable bearing metal 25.

As is usual in constructions of this type, the lower part of the connecting rod cap is provided with an oil dip member which, upon rotation of the crank shaft, passes through troughs such as 26 provided in an oil splash pan 27 secured in the oil pan 10 immediately below and in line with the connecting rod 18. Oil supplied through a suitable pipe such as 28 discharges into the trough 26, and the connecting rod oil dip when passing through the trough 26 at an appreciable speed, splashes the oil out of the trough and on to the various wearing surfaces within the engine, thereby lubricating the same.

It is in connection with such oil dips that this invention is involved and in the drawing is shown an oil dip embodying the pres-

ent invention which is illustrated as consisting of two parts, namely, a securing part 29 and a dip member 30. The securing part 29 is preferably of sheet metal formed to 5 match the lower face of the cap 22 which is preferably machined to present a better joint between the two parts, and is provided with openings 31 to receive the bolts 23. A central opening provided with a down- 10 wardly turned edge 32 is provided in the securing part 29 for closely receiving the dip member 30 which is preferably constructed from a tube the lower end of which is bent towards the direction of rotation of 15 the crank pin 16 and is machined off to present a forwardly presented shovel face to better pick up the oil from the trough 20. The dip 30 projects up through the securing part 29 and the forward and rear 25 portions of this projecting part are separated from the tube along vertical lines each side of the center, forming attaching flanges 33 which are bent over outwardly into contact with the upper face of the 30 securing part 29 and are preferably secured thereto by spot welding or by other suitable means. As shown in the drawing, that portion of the securing part 29 against which the attaching flanges 33 contact is 35 preferably depressed below the upper face of the part 29 an amount equal to the thickness of the flanges 33 so that the upper surface of the part 29 and the lower face of the cap 22 will match perfectly along the 40 edges throughout the entire length of contact. An opening 34 is provided in the cap 22 leading from its lower face to the crank pin bearing surface and the upper projecting end of the dip 30 is adapted to be received in this opening when the part 29 is secured to the cap 22.

In assembling this oil dip to the connecting rod, the connecting rod 18, cap 22 and bolts 23 are assembled as usual with the exception that before the nuts 24 are threaded on to the bolts 23, the oil dip is slipped over the bolts and up against the lower face of the cap 22, the upper projecting end of the tubular member 30 being received in 45 the opening 34 and the bolts 23 passing through the openings 31 in the part 29, after which the nuts 24 are threaded home on the bolts 23, locking all of the parts securely in position. The position of the different parts as progressively assembled is 50 clearly shown in Figure 2.

It will be seen that in this construction, not only is oil splashed out of the trough 55 by the dip member 30 upon rapidly passing therethrough, but oil is also forced up through the dip member and opening 34 to the bearing surface of the crank pin 16. Further lubrication of the crank pin 16 is also provided by the use of openings such as 35 in the connecting rod 18 immediately

above the crank pin 16, which openings are provided to conduct oil splashed thereinto to the upper surface of the crank pin 16 by gravity.

It will be apparent to those skilled in the art that the construction illustrated is particularly desirable from a production and service standpoint and in addition provides a most efficient design of oil dip from the viewpoint of lubrication. 75

Formal changes may be made in the specific embodiment of the invention described without departing from the spirit and substance of the broad invention, the scope of which is commensurate with the appended claims. 80

What I claim is:—

1. An oil dip member for attachment to a connecting rod cap comprising an attaching part and a dip portion, said attaching part comprising a sheet metal member formed to match the lower face of said cap provided with end openings matching the bolt openings in said cap and a central opening, said dipping portion extending through said central opening and having flanges secured to said attaching part. 85

2. An oil dip member for attachment to a connecting rod cap comprising a sheet metal attaching part formed to match a surface of said cap and provided with bolt receiving openings adjacent its ends and a centrally located opening the metal about which is downwardly flanged to form a collar, and an oil dip portion received and secured in said collar and projecting above and below said part. 95

3. An oil dip member for attachment to a connecting rod cap comprising an attaching part and a dip portion, said attaching part comprised of sheet metal formed to match the lower face of said cap and provided with end openings for receiving bolts and a central opening the metal about which is downwardly flanged to form a collar, said dip portion comprising a tubular member received in said collar and projecting above and below the same, the projecting lower part of said tubular member being bent towards the direction of movement of said cap and a portion of the walls of the projecting upper portion being outwardly bent to form flanges for securing said dip portion to said attaching part. 110

4. In combination with a connecting rod cap provided with bolt receiving openings adjacent its side edges and a central opening leading from the bearing surface to the lower face, an oil dip member comprising an attaching part and a dip portion, said attaching part comprising a sheet metal member formed to match the lower face of said cap and being provided with openings matching the openings in said cap, said dip portion comprising a tubular member re- 115

- ceived in the central opening in said attaching part and projecting above and below the same, the lower projecting portion being formed to provide a scoop face and 5 the upper projecting portion being received in the central opening in said cap to locate said part in respect to said cap and being provided with outwardly bent portions to secure said dip portion to said attaching 10 part.
5. The combination with an engine provided with a crank shaft, a connecting rod and cap having crank shaft bearing surfaces, screw means for holding said cap to 15 said rod, and an oil containing trough adjacent the lowest operative position of said cap, of means for lubricating said bearing surfaces comprising an opening in said cap leading from said bearing surface to an exterior face thereof, a sheet metal member 20 provided with an opening matching said opening in said cap formed to match said face and clamped thereagainst by said screw means, and a hollow scoop member received in said opening in said member 25 and secured thereto by flanges on said scoop, said scoop projecting above and below said member, the lower projecting portion lying within said trough when said rod and cap are in their lowest operative position and 30 the upper projecting portion being received in said opening in said cap.

Signed by me at Detroit, Michigan, U. S. A., this 6th day of October, 1924.

GEORGE HUNT.
